DESIGN FOR A COMBINED VEHICLE LAMP AND BRACKET THEREFOR

Raymond A. Donnelly, Newark, N. J.

Application June 1, 1940, Serial No. 92,736

Term of patent 7 years

To all whom it may concern:

Be it known that I, Raymond A. Donnelly, a citizen of the United States, residing at Newark, in the county of Essex and State of New Jersey, have invented a new, original, and ornamental Design for a Combined Vehicle Lamp and Bracket Therefor, of which the following is a specification, reference being had to the accompanying drawing, forming part thereof.

Figure 1 is a top plan view of the combined vehicle lamp and bracket therefor embodying my new design;

Figure 2 is a front elevational view thereof; and.

Figure 3 is a side elevational view.

The dominant features of my design reside in the features shown in full lines.

I claim:

The ornamental design for a combined vehicle lamp and bracket therefor, as shown and described.

RAYMOND A. DONNELLY.
